UNITED STATES PATENT OFFICE.

PERRY BROWN, OF CORAOPOLIS, PENNSYLVANIA; MARGARET J. BROWN EXECUTRIX
OF SAID PERRY BROWN, DECEASED.

DRAFT-RIGGING.

1,344,980.

Specification of Letters Patent. Patented June 29, 1920.

Application filed December 30, 1914. Serial No. 879,705.

To all whom it may concern:

Be it known that I, PERRY BROWN, a citizen of the United States of America, and a resident of Coraopolis, in the county of Allegheny and State of Pennsylvania, have invented certain new and useful Improvements in Draft-Rigging, of which the following is a specification.

This invention relates to improvement in draft rigging for cars and has for its object to provide a tandem rigging of double the ordinary capacity, or one in which I am enabled to utilize two sets of springs in each half of the rigging. The invention consists in the construction shown in its preferable embodiment in the accompanying drawings and hereinafter described and then definitely claimed.

In the aforesaid drawings:

Fig. 1 is a side elevation of a rigging made in accordance with the preferable embodiment of my invention.

Fig. 2 is a vertical longitudinal section of the same.

Fig. 3 is a horizontal section.

Fig. 4 is a vertical section through the line *a—a* of Fig. 3.

Fig. 5 is a vertical transverse section through the line *b—b* of Fig. 3, but with the longitudinal sills and their abutments made separate instead of integral.

Figs. 6, 7, 8 and 9 are perspective views of the various parts detached.

Referring now to the details of the drawings by numerals: 1 designates the ordinary end sill of a car and 2 and 3 designate the draft irons or the intermediate sills. 4 designates the shank of the ordinary draw bar and 5 and 6 designate a pair of side bars which are normally adapted to move backward and forward with the coupler parallel with the said sills 2 and 3, the front ends of the side bars 5 and 6 being secured to the shank of the draw bar upon opposite sides thereof. The forward ends of said plates 5 and 6 are provided with recesses 8 and 9, the top recesses 8 of each side bar being adapted to receive the ends of a connecting plate 10 which passes over the shank of the draw bar immediately in front of the usual shoulder 11. The recesses 9 at the bottom of the front ends of the side bars 5 and 6 are formed in a peculiar manner so that

dove-tail ends 12 and 13 of a securing plate 14 may be inserted through the opening 9 under a shoulder 15 and after the dove-tail ends 12 and 13 are back of said shoulder the plates are moved upward until the dove-tail ends 12 and 13 fit dove-tail recesses 16 immediately over the recesses 9. After the securing plate 14 is thus placed in position, a third plate 17 is slipped in the recess 9 under the shoulder 15 and a cotter or other securing means is passed through coinciding openings in two lugs 18 and 19, the lug 18 projecting from the plate 14 and the lug 19 from the plate 17. The securing plate 14 passes under the shank of the draw bar immediately in front of the ordinary shoulder 20, as seen in Fig. 2. Thus the two plates 10 and 14 co-act with the shoulders 11 and 20 of the draw bar shank and hold the shank to the side bars 5 and 6. At the same time, the dove-tail ends of the securing plate 14 prevents said side bars from spreading. The front ends of the side bars 5 and 6 are provided with abutments 22 and 23, said abutments being reinforced by horizontal walls 24 and 25 (see Fig. 6). The abutments 22 and 23 thus form a means of holding the shank of the draw bar between the plates 10 and 14 so that the aforesaid side bars 5 and 6 and the draw bar are compelled to move together in both directions. In other words, there is a pocket formed between the plates 10 and 14 and the abutments 22 and 23 within which the shank of the draw bar is immovably secured. The draft irons or intermediate sills 2 are preferably formed with abutments 25, 26, 27 and 28 cast integrally therewith although, if preferred, said abutments may be formed separately as indicated at 30 in Fig. 5 and riveted to the intermediate sills or draft irons. This is the only difference between the construction shown in Fig. 3 and the modified construction shown in Fig. 5.

In addition to the abutments 22 and 23 at the forward ends of the side bars 5 and 6, said bars are also provided with ribs 32 running substantially the whole length of the side bars, and substantially at the center of said side bars I form lugs 33 and 34 which are preferably cast integrally with said bars, the ribs preventing buckling of the bars.

Immediately behind the abutments 22 and 23 of the side bars I place the front follower 40 shown in perspective view in Fig. 7, this follower having upper lugs 41 and lower lugs 42 which straddle the side bars 5 and 6 and co-act with the front abutments 25 cast on the draft irons 2 and 3. This follower is also provided with side grooves 43 and 44 into which projects the longitudinal ribs 32 of the side bars 5 and 6. This construction not only assists in securing the front follower in position but aids to prevent the side bars 5 and 6 from buckling.

Substantially midway of the rigging I 15 secure a central block 45 shown in perspective view in Fig. 8. This block is formed with two pairs of lugs 46 and 47 which are dove-tail in shape and pass down between the abutments 26 and 27 on the side bars 5 and 6. These dove-tail lugs therefore prevent the draft irons or sills 2 and 3 from spreading. As an additional safeguard against spreading, a bolt 48 may be passed through the draft irons or sills 2 and 3 and 20 the lower half of the central block 45, an opening 49 being provided in the lower half of the block for this purpose. The central block 45 is made of the peculiar construction shown in Fig. 8 so as to permit the side bars 5 and 6 and their integral lugs 33 to pass 25 between the lugs 46 and 47. On each side of the central block 45 is located a follower, the forward follower being designated 52 and the rear follower 53. The forward of 30 these two followers 52 is designed to co-act with the front follower 40 hereinbefore referred to and these two followers receive the two sets of springs 54 and 55. Likewise, the follower 53 which has been referred to as 35 being immediately behind the central block 45 is designed to co-act with a companion or rear follower 56, shown in perspective view in Fig. 9, the two followers 53 and 56 designed to receive two sets of springs 57 and 58 (see Fig. 2). This rear follower is 40 preferably made of the peculiar construction shown in Fig. 9 and in addition to having grooves 59 and 60 to receive the longitudinal ribs 32 on the side bars 5 and 6, also has dove tail recesses 61 and 62 which are 45 designed to receive similar shaped lugs 63 and 64 cast on the extreme rear ends of the side bars 5 and 6. This rear follower 56 abuts against two stops 70 and 71, the stop 50 70 being secured to or cast integrally with the draft iron or sill 2 and the stop 71 with the draft iron or sill 3. These stops 70 and 71 have slots or recesses 72 and 73 to permit the rear ends of the side bars 5 and 6 to be 55 moved backward as the draw bar receives an "impact." These recesses 72 and 73 are shown in dotted lines in Fig. 1 and in full lines in Fig. 3.

On inspection of Figs. 1, 2 and 7, it will 60 be seen that the followers have central ribs

80 which serve the double purpose of separating the two sets of springs and of forming abutments when the followers come together to prevent crowding the springs.

In operation: On an impact the backward thrust given to the draw bar 4 is received first by the abutment walls 22 and 23 forming the pockets for the shank of the draw bar and is by said abutments transferred directly to the front follower 40 and, through 75 the side bars 5 and 6, to the follower 53. Therefore the followers 40 and 53 are shoved rearwardly, compressing both sets of front springs against the follower 52 and both sets of the rear springs against the follower 80 56. On a pull, the draw bar through the plates 14 and 17, draw the side bars 5 and 6 forwardly and these side bars draw the rear follower 56 forward, compressing the rear springs against the follower 53 and simultaneously draw the follower 52 forward, compressing the other springs against the front follower 40. During these movements, the central block 45 is anchored between the abutments 26 and 27 and therefore receives 85 the thrust in either direction from the followers 52 and 53. On the other hand, the follower 52 is given its forward movement and the follower 53 its rearward movement by the lugs 32 projecting from the side bars 90 5 and 6.

From the foregoing and accompanying drawings, it will be seen that I have constructed a draft rigging of great strength and one which comprises two sets of double 100 springs on each side of the central block 45 so that I have a double tandem rigging.

It will be obvious that changes and modifications may be made in the form and construction of the various parts without departing from the spirit of my invention, the 105 scope of which is set forth by the appended claims.

What I claim as my invention is:

1. In a draft rigging and in combination with the draw bar, a pair of side bars straddling the shank of said draw bar and having abutments forming a pocket into which the shank projects, and a plate co-acting with the shoulder of the draw bar and bridging 115 the space between said side bars.

2. In a draft rigging and in combination with the draw bar, a pair of side bars straddling the shank of said draw bar and having abutments forming a pocket into which the shank projects, and a plate co-acting with the shoulder of the draw bar and bridging 120 the space between said side bars, said plate and said side bars being constructed and arranged to prevent spreading of said side 125 bars.

3. In a draft rigging and in combination with the draw bar, a pair of side bars straddling the shank of said draw bar and having abutments forming a pocket into which 130

the shank projects, said side bars and said shank being secured together so that they travel together in each direction, and a plate co-acting with the shoulder of the draw bar and bridging the space between said side bars.

4. In a draft rigging and in combination with the draw bar, a pair of side bars straddling the shank of said draw bar and having 10 abutments forming a pocket into which the shank projects, said side bars and said shank being secured together so that they travel together in each direction, and a plate co-acting with the shoulder of the draw bar and 15 bridging the space between said side bars, said plate and said side bars being constructed and arranged to prevent spreading of said side bars.

5. In a draft rigging and in combination 20 with the draw bar and followers, a pair of side bars straddling the shank of the draw bar and having abutments located between said shank and the front follower and forming a pocket into which said shank projects, 25 said shank and said side bars and abutments moving together in each direction and said abutments moving the front follower rearward as the shank pushes said abutments on an "impact," and plates co-acting with the 30 shoulders of said draw bar and securing the side bars together.

6. In a draft rigging and in combination 35 with the draw bar and followers, a pair of side bars straddling the shank of the draw bar and having abutments located between said shank and the front follower and forming a pocket into which said shank projects, 40 said shank and said side bars and abutments moving together in each direction and said abutments moving the front follower rearward as the shank receives an "impact," and plates co-acting with the shoulders of said 45 draw bar and securing the side bars together, one of said plates and said bars having respectively dove-tail ends and recesses whereby said plate prevents said bars from spreading.

7. In a draft rigging and in combination 50 with the draw bar and followers, a pair of bars on opposite sides of the followers, said bars having ribs extending longitudinally thereof, said followers being supported by said ribs, whereby said ribs perform the double function of strengthening said bars 55 and supporting the followers.

8. In a draft rigging and in combination 60 with the draw bar and followers, a pair of bars on opposite sides of the followers, said bars having ribs extending longitudinally thereof and said followers having grooves fitting said ribs, whereby said ribs perform

the double function of strengthening said bars and supporting said followers.

9. In a draft rigging and in combination with the draw bar and followers, a pair of 65 bars on opposite sides of the followers, said bars having ribs extending longitudinally thereof, said followers being supported by said ribs, and said bars having projections co-acting with the followers to move the 70 same to compress the springs.

10. In a draft rigging and in combination with the draw bar and followers, a pair of 75 bars on opposite sides of the followers, said bars having ribs extending longitudinally thereof and said followers having grooves fitting said ribs, whereby said ribs perform the double function of strengthening said bars and supporting said followers.

11. In a draft rigging and in combination 80 with the draw bar and followers, a pair of bars on opposite sides of the followers, each bar having abutments forming a pocket for the shank of the draw bar and receiving the blow direct from said shank, a longitudinal 85 rib, a central projection, and a rear lug.

12. In a railway draft rigging, the combination with draft irons, draw bar, and front and rear main stop acting means; of a centrally located plate extending between 90 the draft irons; co-operating means on said plate and draft irons arranged for detachably locking said plate with the draft irons to prevent relative lateral separation therebetween; longitudinally extending side bars 95 detachably connected to the draw bar, said plate being recessed at its ends adjacent the draft irons and within which recesses said side bars are adapted to slide back and forth; front and rear main followers and 100 front and rear intermediate followers, and cushioning means between the sets of followers, said cushioning means and followers extending above and below said side bars.

13. In a draft rigging and in combination 105 with the draft irons, draw bars and followers, a central block immovably held in position, and side bars on opposite sides of said central block having projections co-acting with the intermediate followers to move them 110 with respect to said central block as the side bars are moved, said central block having members straddling the side bars and connected to said draft irons, said draft irons and said block having interlocking parts 115 preventing spreading of the draft irons.

In testimony whereof I affix my signature in presence of two witnesses.

PERRY BROWN.
